UNITED STATES PATENT OFFICE.

ANTHONY JOSEPH WILL AND DAVID ALBERT FELDMAN, OF BALTIMORE, MARYLAND,
ASSIGNORS TO THE AUGUST MAAG COMPANY OF BALTIMORE, OF BALTIMORE,
MARYLAND, A CORPORATION OF MARYLAND.

BAKE PAN.

Application filed September 3, 1925. Serial No. 54,367.

This invention relates to baking pans and particularly to a construction in which a plurality of rectangular pans are secured together side by side so as to be handled as a unit.

This invention provides certain improvements over the construction shown in the patent to J. E. Leamann, Reissue #13,516, January 21, 1913. As pointed out in said patent the outer sides of the end pans of a series receive considerable wear and tear from the tools used for pushing the pans into the oven and drawing them out and said patent discloses the use of plates secured to such outer sides of the end pans to protect the same.

The present invention aims to provide an improved arrangement of such reinforcing and protecting plates and improved and simplified means for securing the same to the sides of the pans without the necessity of having any rivets extend thru the sides of the pans. The advantages of our improved construction will more clearly appear from the following specification taken in connection with the accompanying drawings forming a part thereof, in which drawings:

Figure 1 is a side view of a blank for one of the protecting and reinforcing plates to be secured to the outer sides of the end pans;

Figure 2 is a similar view of such a plate with certain of its edges partially bent over;

Figure 3 is a perspective view partially broken away showing a pan partially completed with one of the protecting and reinforcing plates in position to be bent against the ends of the pan along with the folded corners of the pan;

Figure 4 is a perspective view partially broken away showing a plurality of connected pans with the outer side of the end pan having our improved protecting and reinforcing plate attached thereto;

Figure 5 is a vertical section on the line 5—5 of Figure 4;

Figure 6 is a similar section showing the protecting and reinforcing plate formed somewhat differently at the bottom thereof;

Figure 7 is a horizontal section on the line 7—7 of Figure 4.

Referring to the drawings in detail by the

reference numerals thereon A indicates the 55 separate pans, each of which is provided with a bottom 10, side walls 11, and end walls 12, the walls flaring outwardly from the bottom 10. Any desired number of pans may be secured together so as to be handled 60 as a unit. This is preferably accomplished by arranging a comparatively heavy wire or rod 13 around the upper edge of the pans, this rod being secured to the pans by bending or curling the upper portions of the end walls 12 and the upper portions of the side walls 11 of the end pans down over this rod. To further rigidly secure the pans together, the upper edges of the side walls of adjacent pans are bent to form overlapping 70 flanges 11^b which are securely connected as by rivets 11^c or in any other suitable manner.

In forming rectangular pans of the kind in question it will of course be understood 75 that at each corner there will be produced a V-shaped flap or fold of metal which must be flattened and bent into engagement with the body of the pan. In our improved construction the folds or flaps at the outer corners of the end pans are bent into engagement with the ends of the pans as indicated at 14. The folds or flaps at the other corners of the pans may if desired be bent the same way, as indicated at 14^a. Preferably 80 the material for the pan is so cut that the top of these flaps or folds 14 and 14^a will lie substantially horizontally and closely adjacent to the rod 13 when the flaps are folded against the body of the pans.

The reinforcing and protecting plate which we employ for the outer side of each end pan is indicated at 15 in the drawings. At its upper corners this plate is provided with inclined edges 15^a which are adapted to lie horizontally when the ends of the plate are folded against the ends of the pan as later described. At its lower corners the plate 15 is also provided with inclined edges 15^b which in the intermediate stage shown 100 in Fig. 2 are bent to form short hooks or flanges. The lower edge 15^c of the plate 15 is also bent back upon itself to form a hook or flange as illustrated in Fig. 2. This latter hook or flange may be flattened to form 105 a flat bead 15^d as indicated at the bottom in Fig. 5 or to form a rib 15^e as indicated at the bottom in Fig. 6.

The manner of applying the plates 15 to the sides of the pan is illustrated in Fig. 3. With the folds or flaps 14 flattened and extending at right angles to the ends 12 of the pan, one of the plates 15 is applied to the pan with the hooked edges 15^b engaging beneath the folds 14 of the pan and with the top edges 15^a lying flush with the top edges of the folds. The ends of the plate 15 together with the folds or flaps 14 are now bent closely against the ends 12 of the pans. In this operation the bent or hooked edges 15^b of the plate 15 are compressed so that they form beads which tightly grip the edges of the folds 14 as clearly illustrated at 16 in Fig. 7. This serves to firmly secure the plate to the pan.

It will be understood that the flat bead 15^d or the rib 15^e at the bottom of the plate 15 is formed before the plate is applied to the pan as above described. To facilitate the bending of the edges of the plate 15, as described, and to enable the plate to fit around the lower corners of the pan, the plate 15 is preferably cut away or notched as indicated at 15^f in Figs. 1 and 2. It will be further understood that the end plates 15 are preferably of such width that the upper edges thereof lie just below the rod or bar 13 while the lower edges thereof are substantially flush with the bottom of the pans.

In a construction like that shown and described it will be noted that the outer sides of the end pans present a smooth and unobstructed surface and that none of the metal of which the pan is formed is exposed on the outer sides of the end pans. Such outer sides as well as the outer corners of the end pans are completely covered and protected by the plates 15. The result is that all wear and tear on the ends of the pans is taken by the protecting plates 15 and as a result the life of the pans is prolonged. Furthermore, the manner of securing the protecting plates in position is simple and

obviates the presence of rivet heads inside the pan, thus cheapening and facilitating the application of such plates to the pans.

Having thus described the invention, what is claimed as new and desired to be secured by Letters Patent is:

1. In combination, a rectangular bake-pan, a reinforcing and protecting plate extending along one side of said pan, said pan having flaps at the corners folded against the ends of the pan, said plate having a portion at each end folded against the end of the pan, the folded ends of said plate overlying said folded flaps on the pan and each of said ends having one edge folded over an edge of said flap.

2. In combination, a rectangular bake-pan, a plate extending along one side of said pan, said pan having V-shaped flaps at two corners, said plate having end portions shaped to correspond with said V-shaped flaps on said pan, each of said end portions on the plate having a hook-shaped edge engaging one edge of one of said flaps, said flaps and the end portions of said plate being bent into engagement with the ends of the pan.

3. In combination, a series of rectangular bake-pans arranged side by side, means for securing the pans together whereby the series may be handled as a unit, a protecting and reinforcing plate on the outer side of each of the end pans of the series, and means for securing said plates in position, said means comprising flaps at the outer corners of the end pans and end portions on said plates overlapping said flaps, said flaps and end portions of the plates being bent against the ends of the pans, and said end portions each having one edge bent to embrace the adjacent edge of said flaps.

In testimony whereof we hereunto affix our signatures.

ANTHONY JOSEPH WILL.
DAVID ALBERT FELDMAN.
